(57) **CLAIM**

The ornamental design for a foot caster, as shown and described.

DESCRIPTION

FIG. 1 is a top, left, and front perspective view of a first embodiment of a foot caster showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a top, left, and front perspective view of a second embodiment of a foot caster showing my new design;

FIG. 8 is a front elevation view thereof;

FIG. 9 is a rear elevation view thereof;

FIG. 10 is a right side elevation view thereof;

FIG. 11 is a left side elevation view thereof; and,

FIG. 12 is a top plan view thereof.

The dashed broken lines in the Figures show portions of the foot caster which form no part of the claim. The dashed-dotted broken lines show unclaimed boundaries of the design. The embodiments of FIGS. 1-12 show “left hand” versions of the foot caster; Applicant further claims additional “right hand” embodiments of each of the designs according to FIGS. 1-12, in which each respective figure is a mirror image of that depicted herein.
